CONDENSER FOR LOCOMOTIVES.

Application filed May 10, 1922, Serial No. 559,829, and in Sweden February 15, 1922.

In locomotives driven by steam engines and provided with air cooled condensers it has proved difficult to force the quantity of air necessary for the cooling operation 5 through the condenser by means of fans in such a manner that the necessary vacuum is always available in the condenser. In similar constructions it has previously been suggested to actuate the fans either from the driving wheels of the locomotive or from the main machinery of the locomotive. It being of great advantage to start the locomotive while a good vacuum is prevailing in the condenser, the fans which force 10 the cooling air should be started before the main driving motor of the locomotive. In known constructions this has not been possible unless the fans are actuated from the main machinery which, however, will promote inconveniences and result in too great 15 a consumption of steam for the operation of said fans.

The object of the present invention is to prevent said inconveniences and to provide 20 a simplified actuating device for the fans.

According to the invention this object is attained by the fan or fans being driven by a separate or auxiliary steam turbine, independent of the main steam engine of the 30 locomotive, by the intermediary of a toothed gearing.

The main steam engine and the auxiliary steam turbine preferably co-operate with one and the same condenser by which the advantage is obtained that the effect of the auxiliary turbine will be large owing to the high 35 vacuum necessary for the main steam engine.

The invention is illustrated in the accompanying drawings, in which Fig. 1 shows a 40 complete locomotive according to a preferred embodiment of the invention, whereas Fig. 2 shows a partial sectional view of the auxiliary steam turbine and the toothed gearing in a somewhat modified embodiment.

In said drawings the condenser comprises 45 an air-cooled part 1 and an accumulating receptacle 3. For full description and operation of the condenser reference is directed to the Patent No. 1,407,072. The air used for 50 the cooling operation is forced by the fans 2 each of which is driven by means of bevel gears from the common shaft 6. At the one end the shaft 6 is connected by means of toothed gearing with a steam turbine 16 actuated by live steam from the boiler 18 and

the outlet 16^a of which opens directly into the liquid receptacle 3 pertaining to the condenser. The turbine 16, its toothed gearing, the shaft 6 and the bevel gears of the fan or fans will be more clearly described with 60 reference to Fig. 2.

In the locomotive as illustrated in Fig. 1 the main machinery 12 consists of a steam turbine from which the power is transmitted to the driving wheels 11 by the aid of 65 toothed gearing 9 and coupling rods 10. The driving turbine 16 for the fans is controlled by an admission device 17, which receives steam from the boiler or from the inlet pipe of the main engine. By this admission device 17 the operation of the fans can always be controlled from the driver's cab in order that a suitable vacuum may always be obtained in the condenser as required. 70

The steam turbine 16 is placed above the 75 main turbine 12 and connected to the liquid receptacle 3 between the outlet of the main turbine 12 and the receptacle proper. Consequently, it is placed on the condenser or rather on its accumulator member. 80

The liquid in the receptacle 3 circulates in such manner that the water sprinkles down from the perforated plate 15 through the steam in finely divided jets. The pump 14 which effects the circulation of water 85 from the bottom of the receptacle up to the perforated plate 15, is actuated by the same driving engine 16 as the fans, it being generally of advantage to start said pump 14 at the same time as the fans 2. 90

The pump shown on the drawing consists of a propeller pump coupled directly to the shaft of the rear fan, but obviously said pump may be coupled to any fan shaft, for instance to an intermediate one. 95

By means of this construction the fans may be started or stopped independently of the movement of the locomotive or the operation of the main machinery, and on stopping at a station the fans may continue to cool the condensate so as to effect a high vacuum for the next start of the locomotive from the station. Furthermore the fans may be stopped altogether, when sufficient vacuum is produced in the condenser or when the locomotive runs down an incline, the main machinery being then stopped and no steam delivered to the condenser. 100

According to Fig. 2 the auxiliary steam 110

turbine 16 instead of exhausting directly into the receptacle 3 exhausts into a steam distributing pipe 19 situated above the receptacle 3 and delivering steam to the air cooled part (not shown). The turbine is mounted overhanging, that is to say, only on one side of the turbine wheels, and has its outlet 21 arranged in an axial direction. The turbine is driven by steam from the nozzles 22 and has a very high number of revolutions. The first pinion 23 of the toothed gearing drives a gear wheel 25 attached to the shaft 24. Shaft 24 also carries toothed pinions 26 driving gear wheels 28 attached to the hollow shaft 27. Extending through the hollow shaft 27 is the shaft 6 which is common to all the fans 2 and connected with shaft 27 by means of a diaphragm coupling 29. The turbine disks are made in one piece with the turbine shaft 30 which is hollow so as to attain the same temperature throughout the extension thereof. The turbine shaft 30 is journaled at 31 and 32, between which bearings the shaft is provided with a boss 33 as a counterweight to the turbine. The first pinion 23 of the toothed gearing may be mounted on the turbine shaft by means of a diaphragm coupling 35 and a threaded coupling 34 and by shaft 36 extending through the hollow driving shaft 36^a. The construction and action of the diaphragms is fully described in an application of Fredrik Ljungström, one of the joint applicants hereto, No. 410,193, filed on September 14th, 1920. Mounted within the post 20 is the fan shaft ending at the bottom in a bevel gear 39 meshing with a bevel gear 40 attached to the shaft 6 which is common to all the fans 2. These two gears may be surrounded by a casing 41 which in the embodiment shown is divided at right angles to the plane

of the paper. The lower portion of the casing 41 is mounted on the condenser receptacle 3, whereas the upper portion is attached to the fan disk so as to be able to rotate together therewith. 45

On account of varying temperature in the condenser the height of the steam pipe 19 50 above the condenser receptacle 3 will vary due to the expansion of the different parts of the condenser, so that said pipe 19 cannot be butt-connected in its overhanging portion with the steam discharge pipe 21 55 and the casing of the spur gearing 23, 25, 26, 28. In the embodiment shown said gear casing is rigidly mounted on the steam outlet of the main turbine 12, whereas the steam outlet 21 of the auxiliary turbine 16 60 is resiliently connected with the steam distributing pipe 19 as shown at 21^a. For the same reason the height of the common driving shaft 6 above the condenser receptacle 3 will be variable, but to a lesser 65 extent, the diaphragm coupling 29 having then to adapt itself for the position established.

What we claim as new and desire to secure by Letters Patent of the United 70 States of America is:—

In steam driven locomotives, the combination of a condenser consisting of an air-cooled part and an accumulating receptacle, and a plurality of fans for forcing air 75 through the air-cooled part, with an auxiliary steam turbine for driving the fans by means of intermediate gearing from a common shaft, and means for connecting the exhaust port of said turbine to the accumulating receptacle. 80

In testimony whereof we affix our signatures.

FREDRIK LJUNGSTRÖM.
ALF LYSHOLM.
